(57) **CLAIM**

The ornamental design for a positioning support for a photovoltaic module, as shown and described.

DESCRIPTION

FIG. 1 is a perspective view from a top side of a positioning support for a photovoltaic module showing my new design; FIG. 2 is another perspective view from the top side thereof; FIG. 3 is a perspective view from a bottom side thereof; FIG. 4 is another perspective view from the bottom side thereof;

FIG. 5 is a top plan view thereof;

FIG. 6 is a bottom plan view thereof;

FIG. 7 is a front view thereof;

FIG. 8 is a rear view thereof;

FIG. 9 is a right side view thereof; and,

FIG. 10 is a left side view thereof.
